BELT OR STRAP AND METHOD OF FORMING THE SAME

Filed June 7, 1928

INVENTOR
Wilson J. Tallman
BY *H. H. Simeone*
his ATTORNEY

UNITED STATES PATENT OFFICE.

WILSON J. TALLMAN, OF ROCHESTER, NEW YORK, ASSIGNOR TO HICKOK MANUFACTURING COMPANY, INC., OF ROCHESTER, NEW YORK, A CORPORATION OF NEW YORK.

BELT OR STRAP AND METHOD OF FORMING THE SAME.

Application filed June 7, 1928. Serial No. 283,681.

The present invention relates to belts or straps and a method of forming the same, and an object thereof is to provide a method of forming a shaped end or ends on that type of belt or strap employing a central core and a surrounding covering. Another object of the invention is to provide a belt having a one piece covering for a core which has a reduced end, the covering being stitched about the reduced end.

To these and other ends, the invention consists of certain parts and combinations of parts, all of which will be hereinafter described, the novel features being pointed out in the appended claims.

In the drawings:

Fig. 1 is a view of one face of a strap or belt before its ends are formed;

Fig. 2 is a transverse section through said strap or belt;

Fig. 3 shows the core covering opened at the ends of the strap or belt to expose the core;

Fig. 4 shows the strap or belt with the covering opened and the ends of the core reduced;

Fig. 5 shows a strap or belt with the covering replaced on the reduced ends;

Fig. 6 shows the strap or belt after the covering has been molded about the reduced ends;

Fig. 7 shows the strap or belt after the surplus covering at the ends of the belts has been removed and stitching has been passed through the covering in proximity to the reduced ends; and

Fig. 8 is an edge view of the strap or belt after it has been formed, as shown in Fig. 7.

Straps or belts have heretofore been made having a central web or core formed of various materials and covered by a covering 2 of any suitable material adhesively secured to the web 1, the meeting edges 3 of the covering, in this instance, being illustrated at the center line on one side of the strap or belt. These straps or belts are usually covered by machinery, the web and the covering being formed from strips of uniform widths, so that when removed from the covering machine, the strap or belt has uniform width throughout its length.

It is desirable, in some instances, however, to form ends on these straps or belts which will vary in contour and be reduced with reference to the general width of the belt or

strap. The cutting of such ends of the strap 55 or belt to the desired contour will, however, leave the edges of the core or web exposed.

According to this invention, reduced and shaped ends on covered straps or belts of the class described, are obtained without providing exposed edges of the core or web in the finished piece.

In carrying out this invention, the covered strip, such as shown in Fig. 1, has the end portion of the covering 2 opened at 4 to expose 65 the web or core 1 adjacent one or both ends of the belt or strap, the adhesive preferably being softened by the application of a solvent, heat or otherwise, to permit the separation of the covering from the web or core. The 70 next step is to shape the core to the desired form as shown in Fig. 4 by providing reduced shaped portions 5 by cutting or otherwise. After the shaping of the ends, the covering is closed again upon the core as shown 75 in Fig. 5 and adhesively secured to the core. While not necessary, it is preferred on the next step to place the ends in suitably formed molds in order to cause the covering to conform to the reduced ends, as shown in Fig. 6. The 80 next step is to stitch the covering about the shaped ends by lines of stitches 6. Simultaneously with this stitching, or later, the covering may be trimmed beyond the stitches as at 7 to remove the surplus covering material. 85 The edges of the cut covering may now be colored and polished.

What I claim as my invention and desire to secure by Letters Patent is:

1. The method of shaping an end of a belt 90 or strap having a core and a covering adhesively secured thereover which comprises separating the covering from the core adjacent the end to be shaped, shaping the core to the desired form, adhesively securing the covering over the shaped core end, stitching the covering closely about the core, and removing the surplus covering material about the shaped end.

2. The method of shaping the end of a belt 100 or strap having a core and a covering adhesively secured thereover which comprises separating the covering from the core adjacent the end to be shaped, shaping the core to the desired form, adhesively securing the covering over the shaped core end, pressing the covering in intimate contact with the shaped core end, and simultaneously stitching the

covering closely about the core and removing the surplus covering material beyond the stitching.

3. A strap or belt comprising a core of uniform width having at least one of its ends reduced in width, a one piece covering extending about the core and having its edges meeting on one side of the core, and a stitching connecting those portions of the covering surrounding the reduced end.

4. The method of shaping an end of a belt or strap having a core and a covering secured thereover which comprises separating the covering from the core adjacent the end to be formed, shaping the core to the desired design, replacing the covering over the core, securing the covering on the designed end and removing the surplus covering material about the design. 15

WILSON J. TALLMAN.
